UNITED STATES PATENT OFFICE.

ALBERT T. GIBSON, OF CHICAGO, ILLINOIS, ASSIGNOR TO UNITED STATES SPOT GROUND CORPORATION, OF OMAHA, NEBRASKA, A CORPORATION OF NEBRASKA.

FLOOR AND WALL SCREED-ANCHOR.

1,270,405.

Specification of Letters Patent. Patented June 25, 1918.

Application filed September 12, 1917. Serial No. 190,949.

To all whom it may concern:

Be it known that I, ALBERT T. GIBSON, a citizen of the United States, and a resident of the city of Chicago, county of Cook, and 5 State of Illinois, have invented a certain new and useful Improvement in Floor and Wall Screed-Anchors, of which the following is a specification.

This invention has reference to an anchoring means for firmly securing to walls, floors or other parts of buildings, a screed or ground strip, which, when secured in position, will securely support wall trims or other parts of the building. The object of 10 this invention, broadly, is to provide a simple, inexpensive and durable device of this character, especially adaptable in building construction, and which will firmly and securely hold a screed or ground strip in 15 position.

The invention consists in the novel construction herein described and claimed, and illustrated in the accompanying drawing.

In the drawing forming part hereof:

25 Figure 1 is a front elevation of my improved floor and wall screed anchor;

Fig. 2 is a vertical sectional view of the same;

Fig. 3 is a horizontal sectional view of 30 the same.

Fig. 4 is a front elevation of a portion of a wall, showing a screed or ground strip supported thereon by my improved device;

Fig. 5 is a vertical sectional view of a portion of a wall with the device in position, and

Fig. 6 is a vertical sectional view of a modified manner of anchoring a screed or ground strip.

40 Throughout the various views of the drawings, similar reference characters designate similar parts.

Hereafter, in describing my improved floor and wall screed anchor, I shall refer 45 to the same as applied to a wall. It will be obvious, however, that the same is applicable to walls, floors, ceilings and many parts of buildings for various uses, so I do not limit my invention to any particular 50 use in conjunction with building construction.

In the preferred embodiment of my invention, as illustrated in the accompanying drawing, 1 indicates a flat plate, preferably 55 of metal. I have shown the plate as being

substantially square in outline, although it is clearly obvious that the same may be of any desired configuration to suit the necessary or desired requirements of any particular case.

The plate 1 is preferably provided adjacent its upper and lower edges, with a plurality of apertures 2, for a purpose to be hereinafter set forth. The plate is also provided with a channel or groove 3, extending vertically between the rows of apertures when the device is in use, this groove being formed by slitting the plate and forcing the metal between the spaced apart slits outwardly, as indicated in the drawings.

In Figs. 4 and 5 I have shown the device in use. In those views, 8 indicates a wall or support, to which is applied, at suitable distances apart, spots 6 of an adhesive or plastic substance such as plaster of Paris or the

like. The plates 1 are pressed into these spots and properly aligned therein while the adhesive is in its soft condition. It will be noted that portions of the adhesive 6 pass through the apertures 2 in the plate and spread on the outer face of the plate. After

the adhesive has hardened these plates 1 are thus firmly and securely affixed to the wall. The continuous screed or ground strip 4, which is of wood or any penetrable material, is then secured to the plates by means of the wire 5 on each plate. This wire 5 passes through the slits in the plate and around the back of the plate through the channel 3 and is wrapped and secured entirely about the strip 4, as clearly indicated.

By wiring the strip in position, in the manner indicated, shims can, when necessary or desirable, be driven between the strip and the wall, thus bringing the face of the strip 45 flush to what will be the true surface of the wall. After the strip 4 has been secured in place, in the manner above described, it is surrounded by the plaster 7 in the usual manner, leaving the front face uncovered.

It will be understood that in lieu of the continuous screed or ground strip, an independent block may be attached to each plate if desired.

In the modification of my invention, as 105 illustrated in Fig. 5, I have shown the wire 5 with its ends secured to nails 9 fixed in the sides of the strip 4. In this modification I have shown the strip 4 secured to the plate 1 by means of a nail 10 which acts as a se-

curing means in addition to the wire 5. There are many ways of securing the wire 5 to the plate and of wiring the strip 4 to the plate 1, so I do not restrict my invention to 5 any particular form of carrying this out.

From the foregoing, it is obvious that my invention is not to be restricted to the exact embodiment herein shown, but is broad enough to cover all structures coming within 10 in the scope of the annexed claims.

What I claim is:

1. A device of the class described, comprising a plate, said plate having a plurality of apertures adapted to receive an adhesive, 15 said plate also having a pair of spaced apart slots connected by a channel, and a wire passing through said slots and in said chan-

nel and secured to a ground strip to hold said ground strip connected to said plate.

2. A device of the class described, comprising a flat plate having a pair of spaced apart slots, a channel formed in said plate and projecting from its outer face and connecting said slots, means on said plate adapted to be engaged by an adhesive to support said plate, a ground strip on the outer side of said plate and a wire secured to said strip and extending through the slots and longitudinally through the channel in said plate.

Signed at the city of Chicago, county of Cook and State of Ill., this 4th day of Sept., 1917.

ALBERT T. GIBSON.

Copies of this patent may be obtained for five cents each, by addressing the "Commissioner of Patents, Washington, D. C."
